UNITED STATES PATENT OFFICE.

CHARLES HUGH DUFFY, OF NORTH LAUREL, MARYLAND.

SPARK-PLUG.

1,067,791.

Specification of Letters Patent. Patented July 15, 1913.

Application filed February 6, 1912. Serial No. 675,780.

To all whom it may concern:

Be it known that I, CHARLES HUGH DUFFY, a citizen of the United States, residing at North Laurel, in the county of Howard and State of Maryland, have invented certain new and useful Improvements in Spark-Plugs; and I do declare the following to be a full, clear, and exact description of the invention; such as will enable others skilled in the art to which it appertains to make and use the same; reference being had to the accompanying drawings, and to the letters and figures of reference marked thereon, which form a part of this specification.

This invention relates to spark plugs for internal combustion engines and has for its object to provide a device of this class which will effectually hold the current to cause same to jump the spark gap at the sparking points of the electrodes in such manner that grounding or short circuiting will be prevented.

The current employed in connection with spark plugs for the ignition of internal combustion engines being a high tension current is extremely difficult to hold, and spark plugs are prone to short circuit the current to such an extent that said current instead of jumping across the spark gap follows along the central insulator or core to the metal shell of the plug. This condition invariably results when the central electrode or core becomes coated with a deposit of carbon, soot or oil, and as the spark plug enters the engine cylinder or combustion chamber and is constantly in contact with the products of combustion within the engine cylinder it is practically impossible to prevent a deposit of short circuiting material on the insulator or core and thus short circuit the plug and interfere with, if not entirely prevent ignition. Still another difficulty experienced with spark plugs is due to the accumulation of a drop of oil in which carbon is suspended on the sparking points which bridges the spark gap and acts as a conductor for the current to flow from one electrode to the other across the spark gap instead of jumping to produce a spark. This condition more frequently arises from

an excess of lubricating oil in the engine cylinder and is extremely annoying, and not infrequently results from water entering the engine cylinder from the water jacket. 55

This invention is designed to obviate and overcome the above difficulties and to produce a spark plug which is so constructed and arranged that a short circuiting of the insulating core will not short circuit the 60 current.

A further object of the invention is to prevent the accumulation of short circuiting material on the sparking points and to maintain same in a clean serviceable condition. 65

A further object of the invention is to provide for cooling the central electrode and insulating core to prevent excessive heating, while a further object of the invention is to provide for quick and effective priming of the engine cylinder. 70

With these and other objects in view, the invention consists in the novel construction and arrangement of the insulating core and 75 insulating jacket therefor.

The invention further consists in the arrangement for insulating the central electrode from the metal shell of the plug by providing a plurality of air chambers between the central electrode and the metal shell of the plug. 80

The invention further consists in the novel construction for guarding the insulating plug and insulating sleeve or jacket 85 against a deposit of short circuiting material.

The invention further consists in the novel construction for packing the parts of the plug to prevent leakage. 90

The invention further consists in the novel construction for jetting atmospheric air upon the sparking points and through the spark gap to clean the points.

The invention further consists in the novel construction of the central electrode so as to cool its insulating core. 95

The invention further consists in the arrangement and construction of the ball check and its casing. 100

The invention further consists in applying the physical force or attraction of

capillarity in order to remove from the 65
sparking points any deposit of oil or water
thereon in such manner that bridging of
the spark gap is absolutely prevented.

5 The invention further consists in the
construction which provides for draining ex-
cess liquid from the capillary opening by
gravity.

10 The invention further consists in the con-
struction of the central electrode which pro-
vides for priming the engine cylinder, and
the invention further consists in certain
other novel features of construction and in
combinations of parts, all of which will be
15 first fully described and afterward specifi-
cally pointed out in the appended claims.

The bridging of the spark gap at the
sparking points of a spark plug by a drop
20 of oil or water is due to the capillary attrac-
tion of the oil or water for the surfaces of
the sparking points, and when such a drop
is attracted to the surfaces of the points to
bridge the gap the current flows through
25 the drop and does not jump to produce a
spark.

It is needless for the purposes of a full
description of this invention to go further
into the principle of capillarity other than
to say that the attraction of a liquid in a
30 very small bore, such as the bore of a small
tube, is extremely great, so great in fact
that when a small tube is immersed in water
the water will rise in the bore of the tube
a considerable distance above the surface
35 of the water which is a phenomenon ap-
parently contrary to the law of gravitation.
As a matter of fact the capillary attraction
of the water for the inner walls of the bore
of the tube is greater on the water than the
40 force of gravitation thereon as this attrac-
tion raises the water within the bore of the
tube against the force of gravitation and
overcomes the same. Applying this prin-
ciple of capillarity to the sparking points of
45 a spark plug it will be apparent from an in-
spection of the accompanying drawings
taken in connection with this specification
that the lower electrode of the spark plug
when formed with a small central bore will
50 so attract a drop of oil or water bridging
the spark gap that the bridge will be broken
and the drop of oil or water will be at-
tracted into the bore of the lower electrode.
This capillary attraction only exists when
55 the bores of tubes and the like are very
small, and consequently it is necessary in
applying this principle to the present spark
plug to construct the central bore in the
lower electrode very small but large enough
60 to insert a pin or small wire for the pur-
pose of clearing the same should it be ob-
structed by carbon or any other material
which would prevent a free passage of oil
or water through the same. In applying

this principle to a spark plug and arranging 65
the bore in the lower electrode the capillary
attraction of the water or oil in the bore
of the electrode is further assisted by the
force of gravitation, as in the present in-
stance the passage of the liquid is in a down-
70 ward direction and the force is therefore
greater than it is when inserting a small
tube in water for the purpose of raising the
water within the tube and above the surface
of the water by capillary attraction. 75

Experiments carried on with the construc-
tion in accordance with the accompanying
drawings have shown conclusively that it
is impossible to maintain a bridge of oil
or water between the two electrodes of the 80
spark plug for the very obvious reason that
the capillary attraction of the oil or water
by reason of the bore in the lower electrode
so far exceeds the attraction of the oil or
water to the upper electrode that the bridge 85
is instantly broken and the oil or water is
attracted into and passes through the bore
in the lower electrode. With this brief ex-
planation of this principle as applied to this
spark plug it is thought that the action of 90
the same will be readily apparent.

Referring to the accompanying drawings:
Figure 1 is a vertical sectional view of a
spark plug constructed in accordance with
this invention, and Fig. 2 is a vertical sec- 95
tional view of a spark plug of different con-
struction.

Like numerals of reference indicate the
same parts throughout the two figures in
which—

1 indicates the spark plug which com-
prises the metal shell 2 which is threaded
at 3 for threaded engagement with the cyl-
inder or combustion chamber of an internal
combustion engine. The lower end of the 105
spark plug is provided with a relatively
small central opening 4, and the interior of
the threaded portion 3 is chambered out at
5, the bottom of the chamber 5 being in-
clined at 6 toward the central opening 4 to 110
drain the same. The chamber 5 extends
preferably the full length of the threaded
portion 3 and at the point 7 an inclined
wall 8 is formed which meets the vertical
wall 9 of the upper or enlarged chamber 10, 115
said upper or enlarged chamber 10 termi-
nating at 11 at which point an annular
shoulder 12 is formed, said shoulder 12
meeting the vertical wall 13 of the top
chamber, which top chamber accommodates 120
the insulating sleeve or jacket 14 as is
clearly shown in the drawings.

Referring now to the insulating sleeve or
jacket 14 it will be seen that the same is
provided with an annular shoulder 15 which 125
meets the vertical wall 16 of the sleeve or
jacket, said wall 16 extending downwardly
to the point 17 where it is turned inwardly

to form a guard 18, a relatively small central opening 19 being formed in the guard 18 as is clearly shown in the drawings. The upper portion of the insulating sleeve or jacket 14 is chambered-out at 19 and forms an annular shoulder 20, said chambered-out portion 19 accommodating and receiving the insulating core 21, said insulating core 21 being provided about centrally with an annular swell or enlargement 22 which enters the chambered portion 19 of the insulating sleeve or jacket 14. The insulating core 21 is provided centrally with a bore 23 to receive the central electrode 24, the lower portion 25 of the insulating core 21 being chambered-out at 26 from the end 27 to the point 27 in such manner that an air chamber 28 is formed around the central electrode 24 as will be apparent from the accompanying drawings. It will also be seen that when the insulating core 21 is entered into the insulating sleeve 14 that an annular air chamber 29 is formed around and entirely surrounds the lower chambered portion of the central core 21, and it will also be seen that when the insulating sleeve or jacket 14 is entered into the metal shell 1 that an annular air chamber 30 entirely surrounds the lower chambered portion of the insulating sleeve or jacket, while the guard 18 formed on the lower end of the insulating sleeve or jacket extends inwardly and under the ends of the chambered portion of the insulating core 21. It will also be seen that the inclined wall 8 in the metal shell extends inwardly and under the insulating sleeve or jacket 14 to guard the annular air chamber 30 which surrounds the chambered portion of the insulating sleeve or jacket. This arrangement of a plurality of air chambers surrounding the central electrode 24 is very material to the proper operation of this spark plug, for the reason that a single chamber in the insulation of a spark plug is not sufficient to prevent the passage of the current over the surface of the insulation and ground itself on the metal shell whenever a coating of short circuiting material has been deposited upon the insulation. It is extremely difficult to insulate a high tension current of the character employed for spark plugs and this current uniformly overcomes the resistance of a coating of short circuiting material on an insulator and grounds itself on the metal shell of the plug. By reason of the plurality of air chambers surrounding the central electrode the distance which the current must travel from the central electrode over the walls forming the air chambers to the metal shell of the plug is so great that the current cannot overcome the resistance to ground itself and must therefore jump at the spark gap to produce a spark. As the resistance of

carbon, unlike that of metals, diminishes, as the temperature rises the heat conditions encountered in an internal combustion engine are very favorable to the short circuiting and grounding of the current over and around the walls of the insulator, and unless the insulator is so constructed as to provide a series of air chambers in order to greatly increase the distance over the walls surrounding the air chambers from the central electrode to the metal shell the current will be very quickly and easily short circuited and grounded as soon as a deposit or carbon of other short circuiting material collects upon the surface of the insulator. It is further seen from an inspection of the drawings that the central core 21 is entirely insulated from the metal shell of the plug and that even though the chambered portion of the core 21 is effectually coated with a short circuiting material such a condition could in no sense short circuit the current as said core 21 being insulated from the metal shell a short circuit of the core could not short circuit the current.

Referring again to the drawing, 31 indicates an insulating bushing which rests on the annular shoulder 32 of the central core 21, which annular bushing 31 is engaged by the threaded gland 33, which threaded gland effects a threaded engagement with the threaded portion 34 of the metal shell 1 for the purpose of securing the parts rigidly together as will be apparent. In order to effectually pack the parts to prevent leakage through the plug I provide under the flange 15 of the insulating sleeve or jacket 14 an annular tapered copper gasket 35 which engages the shoulder 12 of the metal shell 1 as is clearly shown, and under the enlarged central portion 22 of the core 21 I provide a similar annular tapered copper gasket 36 which engages the shoulder in the upper portion of the insulating sleeve or jacket 14. As the parts are drawn together these tapered gaskets are compressed inwardly to grip and engage the vertical surfaces of the members in order to insure an absolutely tight joint between the same. It will also be seen that the central electrode 24 is provided about centrally with an enlargement 37, and a gradually tapered copper cone 38 is arranged on the central electrode 24 which bottoms on the enlargement 37 and enters the central bore 23 of the core 21 in order to effect an absolutely tight joint between the electrode 24 and the core 21. The upper end of the electrode 24 is threaded at 39 to receive a knurled nut 40 for holding the secondary terminal 41, while a nut 42 is threaded on the central electrode 24 and against the core 21 to tightly hold the central electrode 24 in position.

Referring now to the lower electrodes 43

it will be seen that the same is preferably connected in the bottom of the threaded portion 3 of the shell which connection can be effected by threads or in any other suitable manner. The electrode being thus arranged is bent or curved at 44 and is then bent to lie vertically the extreme end of the electrode being disposed directly under the central opening 4 in the threaded end of the metal shell 1. The central vertical portion 45 of the electrode 43 is provided centrally with a small bore 46 and is preferably cupped at 47 at the extreme upper end thereof, while the lower end of the bore 46 and the metal shell of the electrode adjacent thereto are beveled off at 48 in order to facilitate the passage of the liquid out of the bore 46 by gravity. The central electrode 24 passing through the chamber 5 within the threaded portion 3 of the shell is bent back upon itself near the end thereof at the point 49 and is again bent back upon itself at the point 50, the lower end 51 of the electrode lying vertically within the chamber 5 and extending centrally through the opening 4 in the bottom of the shell terminating at 52 which is just above the cupped end 47 of the lower electrode 43. The purpose of the bend 49 in the central electrode 24 is to provide an oil drip so that any oil accumulating on the central electrode 24 will run down to the point 49 and drop therefrom instead of passing to the point 52 of the electrode which is the sparking point. This construction prevents any accumulation of oil at the sparking point 2 which might accumulate on the central electrode 24.

The operation of the construction just described is as follows: The current which is led to the central electrode 24 from the secondary wire is prevented from short circuiting or grounding itself on the metal shell of the plug by reason of the construction of the insulation as heretofore described, and consequently the current must produce a spark at the spark gap which is between the point 52 of the central electrode 24 and the cupped end of the lower electrode 43. When, however, a deposit of oil or water is formed on the points of the electrodes to bridge the spark gap, said oil resting in the cupped end 47 of the lower electrode and touching the point 52 of the upper electrode is quickly drawn into the small bore 46 in the lower electrode by capillary attraction governed by the principle as previously described, and as the oil or water passes into the bore 46 it is assisted in its passage through the bore by the force of gravity, which together with the capillary attraction of the oil or water for the bore 26 causes the said oil or water to quickly pass through the bore 46 and onto the bevelled

surface 48 of the electrode, whence the oil runs to the curved portion 44 of the lower electrode and drops therefrom back into the combustion chamber. By means of this construction it is a physical impossibility to maintain a drop of oil between the 70 sparking points of the electrodes as the capillary attraction for the oil for the bore 46 being very much greater than the attraction of the oil for the point 52 said oil will be drawn into the bore 46 and instantly 75 break the bridge. Should, however, in constant use the oil passing through the bore 46 become carbonized the said bore can be instantly cleaned by inserting a pin or other small wire through the bore 46 to remove 80 any deposit therein and to thus maintain the bore open and in operative condition.

Referring to the construction illustrated in Fig. 2 it will be seen that the same differs from the construction shown in Fig. 1 in 85 that an additional expedient is employed to clean the sparking points of a deposit of oil, water or the like. In the construction shown in Fig. 2 the central electrode 24 is provided throughout its length with a central port 53, while the nut 54 at the upper end of the electrode 24 is provided with a seat 55 and houses a ball check 56 which is normally in open position shown in dotted lines in Fig. 2, the upper end of the central electrode 24 being beveled at 57 or otherwise conveniently formed to prevent the said ball check 56 from closing the central port 53 in the electrode 24 when the said ball is in position shown in dotted lines in 100 Fig. 2. The upper end of the nut 54 is threaded at 58 and is provided centrally with a port 59 which communicates with the interior of the nut 54 which port 59 is closed when the ball check 56 is in position shown in full lines in Fig. 2. The terminal retaining nut 60 is cupped at the top as shown at 61 in such manner that a priming charge can be conveniently introduced into the nut 60 which passes through the 110 nut 54 and through the central electrode 24 and thus into the combustion chamber. Near the lower end of the central electrode 24 I provide a guard 62 to act as an oil drip to prevent oil deposited on the central electrode 24 from reaching the end or sparking point of the central electrode 24 as any oil passing down the central electrode 24 runs over the guard 62 and drops off of the depending wall 63.

As far as the construction of the lower electrode 23 is concerned it is the same as the construction first described. While the lower end of the electrode 24 terminates just above the cupped end 47 of the lower electrode 43, the spark gap being formed between the ends of the two electrodes, the removal of the oil by capillary attraction

from the two sparking points is precisely the same as described in the foregoing description.

It will be noted from an inspection of the accompanying drawings that inasmuch as the central electrode insulation is arranged and located in the enlarged chamber 10, which is above the threaded portion 3 of the plug, that said insulation does not extend into the engine cylinder or combustion chamber and is at all times on the outside of the said cylinder or combustion chamber as the outer line of the engine cylinder or combustion chamber is indicated by the line A-B in the two figures; consequently the insulation being arranged as shown is relieved from the excessive heat which it would be subjected to if the insulation extended down into the threaded portion of the plug as is usual in plug constructions. A further advantage of this arrangement is that a large chamber 5 is provided under the insulation and within the threaded portion 3 of the plug so that upon ignition of the gas within the engine cylinder the gases under compression within the chamber 5 rush out through the bottom of the plug and through the relatively small opening 4 therein, which relatively small opening increases the speed of the gases at that point and assists in maintaining the spark gap free and clear of any troublesome deposit.

In the operation of the construction shown in Fig. 2 the ball check 56 is seated as shown in full lines in Fig. 2 during the compression within the engine cylinder and during the power stroke of the piston, but on the intake stroke of the piston the pressure within the engine cylinder being less than atmospheric the ball check 56 moves into position shown in dotted lines in Fig. 2 and causes a draft of atmospheric air to be drawn through the ported electrode 24 and jetted or impinged across the spark gap between the sparking points of the electrodes, thus assisting in keeping the spark gap free from any injurious deposit. This relatively infinitesimal quantity of air which is drawn into the engine cylinder together with the combustible mixture is beneficial to the mixture, while at the same time this draft of air passing through the central electrode has a tendency to cool the same and to prevent undue and dangerous heating of its insulating core. As the illustrations are greatly enlarged over the actual sizes of the plug in order to facilitate the showing of the same it is thought that the construction and operation of the plug will be clearly apparent from the said drawings taken in connection with the foregoing specification.

Having thus fully described the constructions it is apparent that numberless changes

could be made therein which would fall within the limit and scope of this invention and I consider myself clearly entitled to all such changes and modifications as fall within the limit and scope of the appended claims.

What I claim as new and desire to secure by Letters Patent of the United States is:—

1. A spark plug comprising a metal shell closed at one end and provided thereat with a relatively small opening, said plug being provided in its lower portion with a chamber and provided with an enlarged chamber above said first mentioned chamber, an insulating sleeve arranged in said enlarged chamber and shaped to form a guard at its lower end, said lower end being provided with a relatively small opening therein, an insulating core arranged in said insulating sleeve and extending down near the bottom end of said insulating sleeve, said insulating core being provided with a bore to receive the central electrode and provided in its lower portion with a chamber, a central electrode arranged in said insulating core and extending through the said chamber, through the said opening in the bottom for said insulating sleeve, through the lower chamber in the said metal shell and terminating adjacent the said opening in the closed bottom end of the said metal shell, a lower electrode having its end terminating adjacent the end of the central electrode to form a spark gap between the two electrodes, said lower electrode being provided with a small bore extending from the said end thereof and terminating at a point in said electrode in such manner as to provide a passage open at both ends below the said central electrode, said small bore being arranged in close association with the end of the central electrode as to break a bridge of liquid across the spark gap by capillary attraction, an oil drip on the said central electrode near the lower end thereof, means for packing the central electrode, insulating core and insulating sleeve, and means for securing and holding the parts within the metal shell.

2. A spark plug comprising a metal shell having a chamber in the lower portion thereof and having an enlarged chamber in the upper portion thereof, an insulating sleeve arranged in the said upper chamber and terminating at a point above the lower chamber, an insulating core arranged in said insulating sleeve and terminating at a point adjacent the lower end of said insulating sleeve, said insulating core being bored to receive the central electrode and provided in its lower portion with a chamber, a central electrode arranged in said insulating core, the said electrode being surrounded by said chamber, the outer lower wall of said central core and the inner lower wall of said in-

5. A spark plug comprising a metal shell having a chamber in the lower portion thereof and having an enlarged chamber in the upper portion thereof, an insulating core, means for insulating said core from the metal shell, said core being arranged in such manner as to provide an air chamber surrounding the 80 same, the said insulating means being arranged in the metal shell in such manner as to provide an air chamber surrounding said insulating means between said insulating means and the metal shell, a central electrode arranged in the insulating core and insulated from the metal shell by said insulating core and said insulating means, a lower electrode having its end arranged in relation to the end of the central electrode 90 so as to provide a spark gap between the two electrodes and means for exerting a capillary attraction at the end of one electrode to break a bridge of liquid across the 95 said spark gap.
6. A spark plug comprising a metal shell having a chamber in the lower portion thereof and having an enlarged chamber in the upper portion thereof, a central electrode within said metal shell, means for insulating said central electrode from the metal shell, said insulating means having a plurality of air chambers within the same and located between the said central electrode and the metal shell, a lower electrode having its end terminating in relation to the end of the central electrode so as to provide a spark gap between the two electrodes, and means for exerting a capillary attraction for liquid at the end of one electrode 110 to break a bridge of liquid across the said spark gap.
7. A spark plug comprising a metal shell having a chamber in the lower end thereof and having an enlarged chamber in the upper end thereof, a central electrode within said metal shell, means for insulating said central electrode from the metal shell, said insulating means being provided with a plurality of air chambers within the same 115 and between the central electrode and the metal shell, said plurality of air chambers being arranged in such manner as to present a succession of surfaces to resist the passage of an electrical current from the central 120 electrode to the metal shell, a lower electrode having its end arranged in relation to the end of the central electrode to provide
1. An insulating sleeve being arranged to form an air chamber surrounding said chambered portion of the insulating core, the lower outer wall of said insulating sleeve being arranged in relation to the inner wall of the metal shell to form an air chamber surrounding said insulating sleeve, a lower electrode arranged in relation to the central electrode to provide a spark gap between the ends of said electrodes, said lower electrode being provided with a small bore extending from the end thereof at the said spark gap and terminating at a point below the same in such manner as to provide a passage through the same, said small bore being arranged in relation to the end of the central electrode so as to draw liquid therefrom into the said small bore by capillary attraction to break a bridge across the said spark gap, means for packing the central electrode, insulating sleeve and insulating core, and means for securing the parts within the metal shell.
2. A spark plug comprising a metal shell having a chamber in the lower portion thereof and having an enlarged chamber in the upper portion thereof, an insulating sleeve arranged in said enlarged chamber and terminating adjacent the end thereof, the diameter of said insulating sleeve being less than the internal diameter of said enlarged chamber so as to provide an air chamber surrounding said insulating sleeve between said insulating sleeve and the inner surface of the metal shell, an insulating core arranged in said insulating sleeve and extending down into the same, the external diameter of said insulating core being less than the internal diameter of the insulating sleeve so as to provide an air chamber surrounding said insulating core between said insulating core and the said insulating sleeve, a central electrode within said insulating core, said insulating core being provided in its lower portion with a chamber surrounding said central electrode, a lower electrode having its end arranged in relation to the said central electrode so as to provide a spark gap between the two electrodes, and means in the said lower electrode to draw a bridge of liquid from the said upper electrode to break said bridge at the said spark gap by capillary attraction.
3. A spark plug comprising a metal shell having a chamber in its lower portion and having an enlarged chamber in its upper portion, an insulating sleeve arranged in said enlarged chamber to provide an air chamber surrounding said insulating sleeve between said insulating sleeve and the wall of said enlarged chamber, an insulating core arranged in said insulating sleeve to provide an air chamber surrounding said insulating core between said insulating core and the wall of said insulating sleeve, a central electrode arranged in said insulating core, a lower electrode having its end arranged in relation to the end of the central electrode to provide a spark gap for exerting on a liquid bridging the spark gap a capillary attraction to break the bridge.
4. A spark plug comprising a metal shell having a chamber in the lower portion thereof and an enlarged chamber in the upper portion thereof, an insulating core, means for insulating said core from the metal shell, said core being arranged in such manner as to provide an air chamber surrounding the same, the said insulating means being arranged in the metal shell in such manner as to provide an air chamber surrounding said insulating means between said insulating means and the metal shell, a central electrode arranged in the insulating core and insulated from the metal shell by said insulating core and said insulating means, a lower electrode having its end arranged in relation to the end of the central electrode so as to provide a spark gap between the two electrodes and means for exerting a capillary attraction at the end of one electrode to break a bridge of liquid across the said spark gap.

a spark gap between the two electrodes, and means at the spark gap for breaking a bridge of liquid across the spark gap by capillary attraction.

5 8. A spark plug comprising a metal shell, an electrode therein insulated from the metal shell, a fellow electrode arranged in relation to the first mentioned electrode so as to provide a spark gap between the two

10 electrodes, one of said electrodes being provided with a small bore extending from the spark gap end thereof and terminating intermediate said spark gap end and the other end of the electrode to provide an open 15 passage through the same, said small bore being arranged in relation to the end of the first mentioned electrode so as to exert a capillary attraction for liquid bridging the spark gap to break the bridge.

20 9. A spark plug comprising a metal shell, an electrode within the same, means for insulating the electrode from the metal shell, a fellow electrode arranged in relation to the first mentioned electrode so as to provide a spark gap, and means for exerting 25 a capillary attraction for liquid at the end of one electrode to break a bridge of liquid at the spark gap.

10. A spark plug having electrodes arranged in relation to each other so as to provide a spark gap between the electrodes, and means for exerting a capillary attraction for liquid at one electrode sufficient to break a bridge of liquid across the spark 35 gap.

11. A spark plug comprising a plurality of electrodes arranged to form a spark gap, and means at the spark gap for exerting on a liquid bridging the spark gap a capillary 40 attraction sufficient to break the said bridge.

12. A spark plug comprising a metal shell closed at one end and provided therewith a relatively small opening, said plug being provided in its lower portion with a chamber and provided with an enlarged chamber above said first mentioned chamber, an insulating sleeve arranged in said enlarged chamber and shaped to form a guard at its lower end, said lower end being provided 50 with a relatively small opening therein, an insulating core arranged in said insulating sleeve and extending down near the bottom end of said insulating sleeve, said insulating core being provided with a bore to receive the central electrode and provided in its lower portion with a chamber, a central electrode arranged in said insulating core and extending through the said chamber, through the said opening in the bottom for said insulating sleeve, through the lower chamber in the said metal shell and terminating adjacent the said opening in the closed bottom end of the said metal shell, a lower electrode having its end terminating adjacent the

end of the central electrode to form a spark gap between the two electrodes, said lower electrode being provided with a small bore extending from the said end thereof and terminating at a point in said electrode in such manner as to provide a passage open at both ends below the said central electrode, said small bore being arranged in close association with the end of the central electrode as to break a bridge of liquid across the spark gap by capillary attraction, an oil drip on the said central electrode near the lower end thereof, means for introducing a draft of atmospheric air on the spark gap, means for packing the central electrode, insulating core and insulating sleeve, and means for securing and holding the parts within the metal shell.

13. A spark plug comprising a metal shell having a chamber in the lower portion thereof and having an enlarged chamber in the upper portion thereof, an insulating sleeve arranged in the said upper chamber and terminating at a point above the lower chamber, an insulating core arranged in said insulating sleeve and terminating at a point adjacent the lower end of said insulating sleeve, said insulating core being bored to receive the central electrode and provided in its lower portion with a chamber, a central electrode arranged in said insulating core, the said electrode being surrounded by said chamber, the outer lower wall of said central core and the inner lower wall of said insulating sleeve being arranged to form an air chamber surrounding

100 said chambered portion of the insulating core, the lower outer wall of said insulating sleeve being arranged in relation to the inner wall of the metal shell to form an air chamber surrounding said insulating sleeve, 105 a lower electrode arranged in relation to the central electrode to provide a spark gap between the ends of said electrodes, said lower electrode being provided with a small bore extending from the end thereof at the 110 said spark gap and terminating at a point below the same in such manner as to provide a passage through the same, said small bore being arranged in relation to the end of the central electrode so as to draw liquid therefrom into the said small bore by capillary attraction to break a bridge across the said spark gap, means for introducing a draft of atmospheric air on the spark gap, means for packing the central electrode, insulating sleeve and insulating core, and means for securing the parts within the metal shell.

14. A spark plug comprising a metal shell having a chamber in the lower portion thereof and having an enlarged chamber in the upper portion thereof, an insulating sleeve arranged in said enlarged chamber and

minating adjacent the end thereof, the diameter of said insulating sleeve being less than the internal diameter of said enlarged chamber so as to provide an air chamber 5 surrounding said insulating sleeve between said insulating sleeve and the inner surface of the metal shell, an insulating core arranged in said insulating sleeve and extending down into the same, the external diameter of said insulating core being less than the internal diameter of the insulating sleeve so as to provide an air chamber surrounding 10 said insulating core between said insulating core and the said insulating sleeve, a central electrode within said insulating core, said insulating core being provided in its lower portion with a chamber surrounding said central electrode, a lower electrode having its end arranged in relation to the said central 15 electrode so as to provide a spark gap between the two electrodes, means for introducing a draft of atmospheric air on the spark gap, and means in the said lower electrode to draw a bridge of liquid from the 20 said upper electrode to break said bridge at the said spark gap by capillary attraction.

15. A spark plug comprising a metal shell having a chamber in its lower portion and having an enlarged chamber in its upper portion, an insulating sleeve arranged in said enlarged chamber to provide an air chamber surrounding said insulating sleeve between said insulating sleeve and the wall of said enlarged chamber, an insulating core 30 arranged in said insulating sleeve to provide an air chamber surrounding said insulating core between said insulating core and the wall of said insulating sleeve, a central electrode arranged in said insulating 35 core, a lower electrode having its end arranged in relation to the end of the central electrode to provide a spark gap, means for introducing a draft of atmospheric air on the spark gap to cool the electrodes, and 40 means at the spark gap for exerting on a liquid bridging the spark gap a capillary attraction sufficient to break the bridge.

16. A spark plug comprising a metal shell having a chamber in the lower portion thereof and an enlarged chamber in the upper portion thereof, an insulating core, means for insulating said core from the metal shell, said core being arranged in such manner as to provide an air chamber surrounding the 50 same, the said insulating means being arranged in the metal shell in such manner as to provide an air chamber surrounding said insulating means between said insulating means and the metal shell, a central electrode 55 arranged in the insulating core and insulated from the metal shell by said insulating core and said insulating means, a lower electrode having its end arranged in relation to the end of the central electrode

so as to provide a spark gap between the two electrodes, means for introducing a draft of atmospheric air on the spark gap to cool the electrodes, and means for exerting a capillary attraction at the end of one electrode to break a bridge of liquid across the 65 70 said spark gap.

17. A spark plug comprising a metal shell having a chamber in the lower portion thereof and having an enlarged chamber in the upper portion thereof, a central electrode within said metal shell, means for insulating said central electrode from the metal shell, said insulating means comprising a plurality of air chambers within the same and located between the said central 80 electrode and the metal shell, a lower electrode having its end terminating in relation to the end of the central electrode so as to provide a spark gap between the two electrodes, means for introducing a draft of 85 atmospheric air on the spark gap to cool the electrodes, and means for exerting a capillary attraction for liquid at the end of one electrode to break a bridge of liquid across the said spark gap. 90

18. A spark plug comprising a metal shell, an electrode therein insulated from the metal shell, a fellow electrode arranged in relation to the first mentioned electrode so as to provide a spark gap between the two 95 electrodes, one of said electrodes being provided with a small bore extending from the spark gap end thereof and terminating intermediate said spark gap end and the other end of the electrode to provide an open passage through the same, said small bore being arranged in relation to the end of the first mentioned electrode so as to exert a capillary attraction for liquid bridging the spark gap to break the bridge, and means for introducing at the spark gap a draft of atmospheric air to clean and cool the points of the electrodes. 100 105

19. A spark plug comprising two electrodes, one of which is provided with an oil drip near the end thereof to prevent an accumulation of oil at the point thereof, and means for exerting a capillary attraction at one electrode sufficient to break a bridge of liquid connecting the electrodes. 110 115

20. A spark plug comprising two electrodes, one of which is provided with an oil drip near the end thereof to prevent an accumulation of oil at the point thereof, means for breaking a bridge of liquid connecting 120 the electrodes, and means for introducing a draft of atmospheric air at the spark gap to cool the points of the electrodes.

21. A spark plug comprising a metal shell, an electrode within the same, means for insulating the electrode from the metal shell, a fellow electrode arranged in relation to the first mentioned electrode so as to pro- 125

vide a spark gap, and means for exerting a capillary attraction for liquid at the end of one electrode to break a bridge of liquid at the spark gap; said means being positioned to drain excess liquid therefrom by gravity.

22. A spark plug having electrodes arranged in relation to each other so as to provide a spark gap between the electrodes, and means for exerting a capillary attraction for liquid at one electrode sufficient to break a bridge of liquid across the spark gap, said means being positioned to drain excess liquid therefrom by gravity.

23. A spark plug comprising a plurality of electrodes arranged to form a spark gap, 15 and means at the spark gap for exerting on a liquid bridging the spark gap a capillary attraction sufficient to break the said bridge, said means being positioned to drain excess liquid therefrom by gravity.

In testimony whereof, I affix my signature, in presence of two witnesses.

CHARLES HUGH DUFFY.
